GAME BOARD

Carolyn L. Fox, Long Beach, Calif., assignor to Children's Dental Foundation, Long Beach, Calif., a non-profit corporation of California

Application June 16, 1958, Serial No. 51,390

Term of patent 14 years

(Cl. D34—5)

Figure 2 is a fragmentary side elevational view taken along line 2—2 in Figure 1.

I claim:

The ornamental design for a game board, substantially as shown.
